PIN MACHINE.

Patented June 22, 1832.

John I. Howe
Seller's Patent

The invention referred to in these letters Patent and making part of the same contains a description in the words of the said John I. Howe himself of his improvement in the machine for manufacturing pins.

To all whom it may concern. Be it known, that I John I. Howe have invented an improved machine for manufacturing common Pins by means of which the wire is straightened, cut into lengths, headed and pointed; and the pin delivered in a state ready for whitening; and that the following is a full and exact description thereof, and of the manner in which it operates, reference being had to the accompanying drawings which make a part of the Specification. Fig 1. is a perspective view of the machine. Fig 2. a plan showing the principle working parts. Fig 3. a section showing the action for winding the head and cutting off the wire, &c.

Fig 4. a section parallel to the main shaft, showing some of the necessary parts of the machine. Fig 5. end elevation of the uppermost frame, or carriage. Fig 6 vertical section at right angles to the main shaft, with the feeding apparatus &c. Fig 7. section in the same direction, showing the means of opening the pointing forceps and vice jaws. Fig 8 the heading vice and its appendages. Fig 9. apparatus concerned in closing the pointing forceps, &c.

The individual parts of the machine are marked in the respective figures with Roman capitals, with small roman letters, with italic capitals, and with numbers. The same marks on the different figures refer in all cases to similar parts.

A. Head straighting apparatus. B. Head apparatus. C. Pointing forceps. D. Pointing vice. E. Heading vice. F. Pinion on the wind. ing tool.

a. An eccentric cross, combined with a segment having teeth on one which together extend over one half of the circumference of the main shaft, and act during one half its revolutions upon

is an eccentric connected with a pinion which is driven through a reduction gear reduction by the action of B. at each revolution of the main shaft.

The gears, A & B, are each involute, evolved from a circle having for its radius half the distance between the shafts marked at V & K, each of them extending over one quarter of a circle, and from a circle corresponding with the pitch line of the pinions B, to one corresponding with that of the section of 20, on A. In operation they act and revolve upon each other ^{other} in the same direction. This being a new and peculiar mode of obtaining the kind of motion required. I have noted it at greater extent than most other parts of the machine, which, although new in their combination, are not considered as such in their principle of action. C' Wheel, driving the pinions A' they being, to each other as 1. to 1. d. is a wheel or roller having on its periphery a projection and a "conical circular notch", which working upon the system of levers, p. governs the movements of the blade 101 c. f. g. h. i. Band wheels, communicating motion from the main shaft to the printing, feeding, and finishing wheels.

k. a wheel acting on lever 3 carrying back the feeder 3' which inhibits the main drive, & is connected with the spring B.

l. Wheel acting upon a system of levers, carrying back the heading vice-gear, which is brought up by an spring 101

m. m'. Arms with friction rollers at their ends, and acting on cams, which serve to move the carriage 2' back and forth.

n. Wheel giving action to the head vice-increasing apparatus.

o. Lever acting on the feeder 3' p. (use referred to in d)

q. Lever, which by the action of p. operates on 3 a bent lever which keeps open the printing gears, during the required period.

r. Lever, carrying back the heading vice-feeder 3'

s. Head compressor lever. t. Standard on frame 11 for the regulating screw 8' w. carrying regulating the position of the printing gears, previous to their being opened.

x arm connected with a small lever (20) acting between the jaws of the heading vice B. and opening them when required.

y. inclined plane, which by the moving of the carriage (2) acts upon
x. a screw governing the supply of heading wire.

A. Spring, which acting through the lever p &c. elevates the blade. 10)
B. Spring, which by drawing down one arm of the bent lever 3 &c.
forces the shoulder at the extremity of the other arm under the pin
(8) in the lever (18) when said lever is elevated compressing over the
inclined plane (1) on the cam (19).

C. Spring releasing the head compressor B. D.D. Springs which
bring down the catches (W, M.)

E. Spring releasing the lever D. who is lifted from the action of the
wiper K. F. Spring, which elevates the inner extremity of the
apparatus, A to admit the free passage of wire over the stationary blade
10' G. Spring to regulate the position of the clasp, 7) on the ex-
tremity of the head compressor B.

H. Spring to close the vice K. I. Shaft, on the extremities of which
the carriage (2) vibrates. J. Main shaft, from which the per-
ticular motions are derived. K. shaft of the wheel C. and its apparatus.

1. Stationary or permanent frame. 2. Carriage or moveable frame.
3. Feeders, which supplies wire for the bed of the pin.
4. Regulating nut, which by being screwed off, or on, shortens or lengthens
on the pin. 5. Feeders, which supplies the heading wire.
5. 6. Head cutting dies. 7. A clasp which fits snugly on the dies
when they are closed, and serves to prevent their separating when the ram
pressure is made to turn the head. 8. A regulating screw, to gradu-
ate the pressure on compressing the head. 9. A fixture attached to
the frame 1. which at one end has a slot which serves to guide the
arm, " of the ring W. and at the other end" a small pulley ""
10. 10'. Two blades, with cutting edges, which serve the purpose
of cutting nippers or pincers, for holding the two wires while the head-
ing wire is winding around them, and the feeders are carried
back, and then at the proper time cutting off both wires.

11. 11' to 12. 12' Guides. 13. 13' Wires which lift the catchers.
 14. 14' Catchers which respectively retain the carriage. 15. in a fixed position during certain stages of the operation of the machine.
 16. A pulley by means of which the pointing wheel D receives its motion from the wheel C.
 17. A spring which carries up the feeder 3.
 18. A lever which serves to open the pointing forceps C.
 19. A cam which serves to elevate the lever 18.
 20. A iron placed between the jaws of the vice E to separate them at the proper period in the operation of the machine.
 21. Straightening wire. 22. Lipe on the winder.
 23. 23" spiral springs which act upon the carriage C, drawing it towards the centre when it is inclined to one side or the other. 24. Wrench. 25. 25' Gains on the carriage E.
 26. Eccentric pin or crank attached to the shaft of the pointing forceps C. The drawings, with the exception of the perspective view (fig 1), are on a scale reduced about one half from the actual machine. The skillful mechanist by an examination of the foregoing references and the accompanying drawings will readily trace the general operation of the machine, and will perceive that two separate wires are introduced one for the formation of the body and the other that of the head of the pin. The wire for the body is passed in between the straightening jaws 3. 3' of the feeder fig 4. It passes thence through the head winder A which is tubular, and also between the cutting blades 10. 10'. The space between the straightening jaws is regulated by the screws marked 1", "", "", . These operate upon the common principle adopted for straightening such wire.

The wire for the head is passed between the jaws of the feeder 3. The end of it passing between the blades 10. 10'. The jaws of the feeder are made to hold the wire with sufficient firmness by means of a screw. In this situation of the machine the wire for the body of the pin, passes on from right to left from the feeder 3.

to No. 7, and lies between the cutting edges of the blades, 10. 10'. The heading wire also passes between these blades, but from left to right and in this case if the machine be set in motion, the various parts which concur in the formation of the pin will be simultaneously or successively acted upon. In forming the head of the pin, the moveable blade 10, holding the two wires, firmly between their edges, the head under A will revolve, catching the end of the heading wire in a lip or projection D.D. at its end and winding it spirally upon the body wire in contact with the blades. These movements are effected in the following manner. The eccentric curve or ring connected with the segment of cage of fig 3. Comes in contact with the eccentric connected with the pinion b on the shaft K (fig 3.) the former carrying the latter forward until the teeth of the segment A. Strike into gear with the teeth of the pinion b. In this part of the movement, each of the shafts J & K passes through one fourth of a revolution; in the subsequent part of the movement, that is when the segment A acts upon the pinion b. The main shaft J passes through one fourth whilst the shaft K passes through $\frac{3}{4}$ of a revolution; so that K makes one entire revolution, and J but one half, and the pinion on the inner A is driven through four revolutions during half a revolution of J and is at rest during the other half, at which period the operations are effected preparatory to the winding of another head.

As some of the respective operations go on simultaneously, it may be supposed that previously to the winding process just described, other heads had been wound. The head of each and the pin cut off and taken into the pointing device, and carried to the pointing wheel, I shall however carry the one on which I have supposed the head to be wound, through its individual stages. When the pointing jowels have arrived in a position to take hold of a pin, the head of which has been completed, the wheel d. will have arrived at the position in which it is shown in fig 6. The forceps will then be closed on the pin previously projected, and the wires cut off by the action of the wheel d. which will deposit the moveable blade upon the fixed one. Immediately after the movement last described,

wood those for feeding in the wire for the body of the skin: The moveable blade is raised, and the front end of the windor, A. is elevated. The former is effected by the spring A. acting on the lever, P. and its appendages, the friction rollers " " falling into the notch " in the wheel, C. as shown in fig 3. The latter takes place immediately upon the cutting off the wire by means of the spring, P. (figs 1 & 2) a wire from which descends to the frame in which the windor A. rests, and which it lifts to a distance requisite to allow the body wire of the skin, with the unfinished head on it to pass freely over the stationary blade, 10.

The jaws of the heading vice H , being at this time open, and the feeders 3 & 4 S , being released from the action of their respective wipers, are brought up by the springs, shown at E & F fig. A , and at 17 & 18 fig. C . The feed or 3 , is drawn forward, the wire with the unfinished head is thereby advanced between the blades of the heading vice, which closes on it by the action of the spring H , embracing it just at the back of the unfinished head. The pointing forceps, had seized the one previously headed, and carried it to the pointing wheel, by the lateral motion of the carriage 2 , which at the same time brings the heading apparatus B , opposite the unfinished head. The wiper N , upon the shaft J , advances the die on this end of B , to pierce and finish the head. The carriage 2 , again vibrating whilst the jaws H , are opened by the lever G , the pointing forceps, having opened, and dropped their pointed iron, glass between the jaws H , and with the newly headed pin. A new vibration of the carriage removes the forceps, with their charge, bringing the unfinished point against the revolving pointing wheel D .

The pulley of the spinning wheel shaft, comes in contact with and receives a rotary motion from the wheel, b , driven by a band from the wheel b , fig 1. The ground of the pin consequently revolves on the revolving wheel, D , and there receives a regular conical point.

The pointing wheel is formed of two circular plates of steel, bevelled on their edges, and anited by their smaller faces, thus, forming a groove.

The bevelled edges are formed on the teeth or flats of the requisite form; the bevels in the two plates may be made of different angles to avoid the necessity which would otherwise exist on the front. The parting wheel

may vary in its velocity, ranging between 50 and 100 revolutions for one of the main shafts. During the pointing the carriage remains stationary, being held in a fixed position by the catch 14. (fig 5.) holding upon the pin 15. which prevents its moving towards the centre, whilst being drawn by the spring, 23. towards the centre, it is prevented from receding farther. The mode of engaging and disengaging this catch will be made manifest by attention to the drawings, and the references to them. Connected with the motion of the carriage (21) are several others, which must be simultaneous, to be performed. One of these is, the giving to the pointing forceps, their proper position for seizing the next pin, that is, with its lower jaw downwards. This is effected by means of the concave pin 26. on the back end of the shaft of the pin 21. embracing this pin, and being acted upon by a weight and cord passing over a pulley turns the forceps from any other position, into that required; the manner of opening the pointing forceps, is shown in Fig 7. where the carriage is supposed to be moving from right to left. C. is a section of the forceps shaft, and S. a section of the arm (1. fig 2.) connected with the movable blade of said forceps near its extremity. In the motion of the carriage, the pin "projecting from the side of the lever 18. slides upon the inclined plane 19 carrying the lever up against the arm C. 1, and pressing it against the shaft of the pointing forceps, depressed the movable jaw. This, and the subsequent action of closing it, as well as many of the individual parts of the machine, may be variously modified, so as to answer the same end, and do not therefore require to be minutely described, as every competent work man would actually make such variations, whilst the general principle of the action of the whole apparatus would be still retained.

Although the individual parts of the before described machine, such as, the lever, arms, rifiers, forceps, dies, wheels, pinions, and other appendages, are the common elements of many other machines, and several of them have been used in instruments for manufacturing pins, and can not therefore be claimed as new. I have yet so combined them as to give a specific character and action to my machine, producing by these new combinations, new and useful results, and it is therefore ap-

in this combination of parts, that it mainly rest my claim to its valueless use, and, besides, this general arrangement, I claim the specific arrangement of the apparatus, by which the winding of the wire to form the head of the pin, is effected, and I also claim the peculiar arrangement of the eccentric curves and segments, represented in Figure 6, the main rotary fluster, of which are marked A, B, C, which arrangement produces a rotary motion varying in its velocity, and which may be advantageously applied in the construction of other machinery where such a motion may be advantageous. Such application how ever to any machine will.... be considered as a violation of my right."
